CLAIM

The novel ornamental design for a LED stacker bulb lock, as shown and described.

DESCRIPTION

FIG. 1 is a perspective exploded view of the LED stacker bulb lock;

FIG. 2 is a perspective view of the LED stacker bulb lock as used;

FIG. 3 is a perspective exploded view of the LED stacker bulb lock as used in accordance with the present invention; FIG. 4 is a top plan view of the LED stacker bulb lock showing the section cuts for FIGS. 9-10, with the bottom plan view being a mirror image;

FIG. 5 is a back elevational view of the LED stacker bulb lock;

FIG. 6 is a front elevational view of the LED stacker bulb lock;

FIG. 7 is a right-side view of the LED stacker bulb lock;

FIG. 8 is a left-side view of the LED stacker bulb lock;

FIG. 9 is a cross-sectional view from the cut line 9-9 illustrated in FIG. 4 of the LED stacker bulb lock; and, FIG. 10 is a cross-sectional view from the cut line 10-10 illustrated in FIG. 4 of the LED stacker bulb lock.

The broken lines in the drawings illustrate portions of the LED stacker bulb lock which forms no part of the claimed design.
